UNITED STATES PATENT OFFICE.

PAUL G. SCHWARZ, OF INDIANAPOLIS, INDIANA, ASSIGNOR TO DREW ELECTRIC AND MANUFACTURING COMPANY, OF INDIANAPOLIS, INDIANA, A CORPORATION.

FEEDER CLAMP FOR OVERHEAD TROLLEY SYSTEMS.

Application filed December 22, 1919. Serial No. 346,639.

To all whom it may concern:

Be it known that I, PAUL G. SCHWARZ, a citizen of the United States, residing at Indianapolis, in the county of Marion and State of Indiana, have invented certain new and useful Improvements in a Feeder Clamp for Overhead Trolley Systems, of which the following is a specification.

This invention relates to a so-called feeder clamp adapted to be used in overhead trolley systems, and the invention consists more especially in the portion of the said clamp which provides for making working engagement with the feeder cable or conductor, all substantially as shown and described and particularly pointed out in the claim.

In the accompanying drawings, Fig. 1 is a side elevation of the clamp as a complete unit and of a section of a trolley wire engaged therein, and Fig. 2 is a cross section on line 2—2, Fig. 1.

The clamp as thus shown is of the two-part screw type adapted to engage a side grooved trolley wire therein, as is now a more or less common practice with screw clamps or clamping ears of various designs and constructions, and therefore I do not lay claim to the clamp in this particular or in so far as its engagement with the trolley wire is concerned, nor, on the other hand, do I limit myself to the particular style or form of clamp shown. That is, I may employ any one of many forms of feeder clamps now known, provided that it embodies the essential novelty of the present clamp, and which consists in a suitable clamping member *c*, of whatever type, provided with a boss, head or projection *2* at its middle and top having an oval hole, socket or opening horizontally therein and adapted to receive a feed-in conductor or cable, not shown. The said oval hole or socket *3* terminates within the said head in the present showing, but not necessarily,

and looked at in cross section the said slot or opening stands or has its greater depth vertically and is penetrated at its top by two set screws *4*. The said screws are of such reduced size as compared with the said socket or opening that they will fill the width of the opening by $\frac{1}{2}$ " clearance on either side, this preventing any of the wires in a wire cable or conductor from slipping between the said screws and the side walls of the opening and insuring a good contact between all of the cable wires and the clamp. The oval hole or socket also, as compared with a round hole, has the material advantage of receiving strands from 1/0 to 4/0, and in case it is desired to use a size of cable larger than 4/0, which may be regarded as the transverse size of the hole or opening *3*, the cable can be readily flattened more or less to enter the opening. Solid wire instead of a stranded cable also may be used up to 4/0, and the clamping by set screws *4* can be made effective without slugs, shims or other like devices.

Furthermore, this clamp can also be used as a soldered on connecting medium, owing to its cast construction, and with the set screws in place, the thread will prevent the solder from running out.

What I claim is:

A feeder clamp for trolley wires having an elongated round boss offset transversely at its top, said boss being provided with an oval opening horizontally at one end and closed at its opposite end, and a pair of set screws entering said opening from the top adapted to secure a cable therein, said opening having its major oval dimensions extending vertically in line with the axes of said set screws.

Signed at Indianapolis, in the county of Marion and State of Indiana, this 18th day of November, 1919.

PAUL G. SCHWARZ.
